(57) **CLAIM**

The ornamental design for a stacked electrical connector, as shown and described.

DESCRIPTION

FIG. 1 is a front, top and right side perspective view of a stacked electrical connector showing our new design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top plan view of FIG. 1; and,

FIG. 7 is a bottom plan view of FIG. 1.

The broken line showing of the environment is for illustrative purposes only and forms no part of the claimed design.
